WELL DRILLING APPARATUS

Welton J. Williams, Brownfield, Tex.

Application February 12, 1951, Serial No. 210,516

7 Claims. (Cl. 166—19)

1

The present invention relates to rotary well drilling equipment, and more particularly to apparatus for circulating drilling fluid through and around core drilling mechanism, and well clean-out bailers or junk-fishing tools.

Clean-out bailers or junk fishing tools are used in rotary well drilling equipment for removing debris from the well bottom. They usually consist of a tubular body with debris catchers in the bore or chamber thereof. Debris, such as bit pieces, cones reamer blade and all such junk metal, is forced off the well bottom and upwardly into the chamber by circulation of drilling fluid or "mud." In operating such tools, the well fluid is pumped downwardly in the annular space within the well casing and around the drill stem or "drilling string." The downward movement of such fluid is stopped by the well bottom, and the fluid then travels upwardly through the bore of the tubular body, with the junk pieces being entrained in the fluid so that they are carried upwardly above the debris catchers therein.

Such a junk fishing tool is disclosed in United States patent numbered 2,169,922, which was issued August 15, 1939, to J. H. Notley.

Conventional core-bits consist substantially of a tubular bit body, the lower end of which consists of an annular row of cutting teeth. The body is attached to the lower end of the drilling string to form a continuation thereof, and is rotated by rotation of the drilling string, which in turn is driven by power applied to its upper end above the earth's surface.

Like the above described bailers or junk fishing tools, the drilling fluid is forced downwardly through the annular space, and then passes upwardly in the bit body or core barrel. Such a core drilling mechanism is disclosed in United States patent numbered 2,100,311, which was issued on November 30, 1937, to A. C. Catland.

An object of the present device is to provide a tool which is adapted to be installed in the drilling string, at a point next above a junk fishing tool or core barrel, such tool making it possible to pump the well fluid downwardly through the drill-string, instead of the annular space.

Another object is to provide a wash-out tool so designed that well fluid may be selectively circulated both upwardly through the core barrel or the debris catcher.

A further object is to provide a wash-out tool which may be installed in the drilling string directly above any conventional debris catcher or core barrel, and which, when so installed, will function to produce reverse circulation through either, with the wash-out liquid being initially delivered downwardly through the drilling string regardless of the direction it flows through the barrel or catcher.

Other objects will be apparent from the following description when taken in conjunction with the accompanying two sheets of drawings, where-in:

2

Figure 1 is a vertical sectional view of the mechanism before the packer thereof has been expanded, and showing the lower end of the mechanism operatively connected to the upper end of a conventional core catching tool;

Figure 2 is a fragmentary vertical sectional view of the remainder of said core catching tool;

Figure 3 is a fragmentary vertical sectional view of the mechanism with the packer expanded; and,

Figures 4, 5, 6 and 7 are horizontal sectional views taken respectively along the lines 4—4, 5—5, 6—6, and 7—7 of Fig. 1.

Like characters of reference designate like parts in those figures of the drawings in which they occur.

In the drawings:

The reference numeral 1 indicates the lower end of the lowermost section of a conventional 20 drill stem or pipe-string of rotary well drilling apparatus, and the reference numeral 2 indicates a string of conventional well casing which is anchored in a well, not shown.

The device, per se, consists substantially of a 25 tubular body which is composed of two tubular sections. The upper section is indicated by the reference numeral 10 and the lower section by the numeral 11, and the two sections are connected together in axial alignment by threads 12. The upper end of the body section is provided 30 with tool-joint threads 13 by which it is connected to the lower end of the pipe section 1. The lower end of the body section 11 is equipped with tool-joint threads 14 by which it is connected to the upper end of a conventional core barrel 3.

Although the core barrel 3, and its supported 35 core drilling bit 4 therebelow, are adapted to be used in conjunction with the mechanism of the present invention, it does not form an actual part 40 of the invention. Such conventional core taking tools usually include a plurality of annularly spaced bit blades 5 mounted on the lower end of the bit 4, which is in turn connected to the lower end of the core barrel 3. The tool usually includes one or more sets of radially spaced fingers 45 6, which are pivotally mounted in the bore 7 of the bit body 5 to prevent downward escape of a core, or of debris, which enters the barrel 3 through its open lower end.

The elements indicated in the drawings by the 50 reference numerals 1 through 7 are conventional parts of conventional equipment, and are not parts of the present inventive mechanism, per se.

The lower body section 11 of the inventive mechanism has an upwardly presented annular 55 shoulder 15 with a reduced bore 16 extending therebelow, and the lower end of the bore 16 is again reduced in diameter by an upwardly presented annular shoulder 17, which also forms a ball seat, as is more fully described hereinbelow.

A lower bore 18 extends downwardly from the shoulder 17 to the lower end of the body section 11, and is flared downwardly and outwardly as

shown, to coincide in diameter at its lower end with the upper end of the bore 19 of said core catching barrel 3. The upper end of the lower section 11 is indicated by the numeral 21.

Intermediate its ends, the exterior surface of the upper body section 10 is abruptly reduced in diameter to form an upper shoulder 20, with the cylindrical surface 22 therebelow being perfectly smooth (Fig. 3). Adjacent the upper end of the reduced surface 22, the wall of the section 10 is provided with two oppositely disposed through slots 23 and 24 which are elongated vertically.

Surrounding the surface 22, there is provided a resilient tubate packer or sleeve 25 having its upper end vulcanized to a metal ring 26 which is slidable vertically with relation to the surface 22. The lower end of the sleeve 25 is vulcanized to a metal ring 27, which seats upon a resilient gasket 28, which is supported upon the upper end surface 21 of the lower body section 11. A similar gasket 29 is provided around the surface 22 below the shoulder 20 and above the ring 26.

The axial bore of the upper body section 10 is indicated by the reference numeral 30, and slidably disposed within this bore 30 there is provided a tubate sleeve 31. The sleeve 31 is rigidly connected to the upper ring 26 of the packer by two horizontal studs 32 and 33 which respectively extend through the slots 23 and 24 in the wall of the body section 10. The arrangement is such that downward movement of the sleeve 31 causes a similar movement of the upper end portion of the packer sleeve 25, which deforms the sleeve from the cylindrical form of Fig. 1 to the centrally distended configuration of Fig. 3. When deformed as illustrated in Fig. 3, the sleeve 25 is forced into sealing engagement with the well casing 2.

Within the confines of the tubular wall of the sleeve 31, and extending from end to end thereof, there is provided a plurality of radially spaced channels 34. The channels 34 permit passage of fluid through the sleeve 31, even though its bore 45 is closed, as is more fully described hereinbelow.

Beneath the lower end of the sleeve 31, and with its lower end seated upon the shoulder 15 of the lower body section 11, there is provided a helical expansion spring 35 which resists downward movement of the sleeve 31.

Within the confines of the tubate wall of the lower body section 11, there is provided a plurality of radially spaced vertical fluid passages 36. The upper ends of the passages 36 terminate in an annular groove 37 which is partially formed in the shoulder 15 and partially in the lower end surface of the upper body section 10.

The wall of the upper body section 10 is provided with radially spaced vertical passages 38, which extend from the groove 37 upwardly to a point above the packer, and then slant outwardly to emerge at the outer surface of the section (Fig. 1). The groove 37 acts to insure communication between the adjacent ends of the passages 36 and 38, regardless of the relative radial positions of the body sections 10 and 11.

Slanting downwardly and outwardly from the upper bore 16 of the body section 11, and passing through the wall thereof, there is provided a plurality of fluid ports 39. Fluid may pass downwardly through the channels 34 or the bore 45 of the sleeve 31 to reach the bore 30 of the upper body section 10, and may flow from the bore 30 to the smaller bore 16 in the lower body section 11. The ports 39 permit escape of the fluid from

the bore 16 to the annular space 40 lying between the body and the well casing 2. This annular space is illustrated in Figs. 2 and 3, and is indicated by the reference numeral 40.

Operation

The mechanism, with the sleeve 31 and packer 25 in the condition illustrated in Fig. 1, is lowered into the cased well with the core barrel 3 and bit body 4 attached therebelow, as illustrated, or with a conventional debris catcher installed in lieu thereof, if desired. During this lowering operation, the casing is ordinarily full of drilling fluid or "mud," and the vertical bores 30, 45, 16, 18, 19 and 47 are all completely open, so that the mechanism may readily travel downwardly through the mud without any plunger action.

The lowering operation is continued until the bit blades 5 are adjacent the well bottom 50. The mud circulating pump on the earth's surface is started, and fluid is circulated downwardly through the core barrel and bit to wash cuttings or debris upwardly into the annular space 40 so that the bit blades may be seated upon the well bottom.

When the bit blades are thus seated, the mechanism is in position to drill an annular hole, with its center left connected to the well bottom. However, before the pipe string is rotated to start "cutting hole," a steel ball 51 is inserted within the upper end of the pipe string. The ball 51 descends with the mud, and finally lodges upon the seat 47 to close the bore 48 in the body section 11. Since the downwardly traveling fluid cannot thereafter pass through the bore 18, its path is diverted downwardly and outwardly through the outlet ports 39 to the annular space 40. In reaching the upper ends of the ports 39, the fluid passes from the pipe string downwardly through the bore 45 and channels 34 of the sleeve 31 to enter the bore 30 of the body section 10, from whence it flows into the bore 16 and channels 38.

Following the dropping of the small ball 51, and after it has had time to ledge in its seated position as shown in Fig. 1, a second and larger steel ball 52 is dropped into the pipe string. This second ball gravitates to a seated position upon the upper end of the sleeve 31, and closes the bore 45 thereof. When the ball 52 is thus seated the sleeve 31 is forced to move downwardly in the bore 30, with the horizontal studs 32 and 33 moving downwardly in the guide slots 23 and 24 in the wall of the body section 10. Downward movement of the sleeve 31 causes a similar movement of the upper packer ring 26, and consequently, the packer sleeve 25 is expanded into sealing engagement with the well casing 2 (Fig. 3).

After the larger ball 52 is seated and the packer 25 is expanded, the fluid is still free to pass downwardly through the vertical channels 34 in the wall of the sleeve 31, and downward circulation may therefore be maintained through the outlet ports 39 to the annular space 40.

After the packer has been expanded, fluid entering the annular space 40 can no longer travel upwardly in the annular space, and consequently, it follows the line of least resistance and enters the bore 7 of the bit 4 by passing between the blades 5. The fluid then travels upwardly through the bore 19 of the barrel 3, and enters the lower ends of the vertical passages 36 in the body section 11. The upwardly moving fluid then passes into the annular groove 37, and thence into the lower ends of the passages 38 in the upper

body section 10, through which it travels to the annular space 40 at a point above the packer 25. The circulating fluid returns to the earth's surface via the annular space.

During rotation of the pipe string and of the above described mechanism to accomplish the core drilling operation, the expanded packer rotates with the mechanism, and during this rotation it scrapes or rubs against the inside surface of the well casing 2. For this reason, the channels 34 in the sleeve 31 are bored in such diameters that their combined areas are only slightly less in area than the combined areas of the outlet ports 39. Consequently, the expanding pressure on the packer is not sufficient to cause an excess of wear upon the external surface thereof.

When fluid circulation is discontinued, the spring 35 acts to return the sleeve 31 to the upper end of its travel, and to thereby return the packer to the condition shown in Fig. 1.

Obviously the invention is susceptible to some change or alteration without defeating its practicability, and I therefore do not wish to be confined to the preferred embodiment shown in the drawings and described herein, further than I am limited by the scope of the appended claims.

I claim:

1. A reverse circulation wash-out mechanism to be run in a cased well on the lower end of a pipe-string extending downwardly in the well from the earth's surface to adjacent the well bottom, said mechanism being positioned above a debris or core catching tool, and including: a tubular body having its upper end threadedly connected to the lower end of the pipe-string, and having its lower end connected to the upper end of said tool; an axial bore in the upper portion of said body; a reduced upwardly presented shoulder in said bore and forming a ball seat; a second bore extending axially through the body below said seat; radially spaced fluid outlet ports extending from the upper bore outwardly through the wall of the body; a tubular sleeve slidably disposed in said upper bore; a ball seat on the upper end of said sleeve; longitudinal flow passages in the wall of said sleeve through which fluid may flow when its bore is closed; a resilient packer around the body, said packer connected to the sleeve and expandable by downward movement thereof; and radially spaced vertical passages in the wall of said body, said passages extending upwardly from the lower bore to a point above the packer, and thence outwardly through the body wall above said packer.

2. Structure as specified in claim 1, and: a ball adapted to be dropped through the pipe string, through said sleeve, and through said upper bore, into seated position upon the lower seat.

3. Structure as specified in claim 1, and: a ball adapted to be dropped through the pipe string, through said sleeve and through said upper bore, into seated position upon the lower seat; and a second ball of larger diameter adapted to be dropped into seated position upon the upper end of said sleeve.

4. Structure as specified in claim 1, and: a ball adapted to be dropped through the pipe string, through said sleeve, and through the upper bore, into seated position upon the lower seat, after which any fluid pumped downwardly through the string is forced outwardly through said ports to the annular space in the well casing, said fluid thence traveling upwardly through the lower end of said tool to the lower bore of the mechanism and into said passages.

5. Structure as specified in claim 1, and: a ball adapted to be dropped through the pipe string, through said sleeve, and through the upper bore, into seated position upon the lower seat, after which any fluid pumped downwardly through the string is forced outwardly through said ports to the annular space in the well casing, said fluid thence traveling upwardly through the lower end of said tool to the lower bore of the mechanism and into said passages; a second ball of larger diameter adapted to be dropped into seated position upon said sleeve, whereby downwardly traveling fluid in said string acts to move the sleeve downwardly to expand the packer into sealing engagement with the well casing.

6. A reverse circulation wash-out mechanism to be run in a cased well on the lower end of a pipe-string extending downwardly in the well from the earth's surface to adjacent the well bottom, said mechanism being positioned above a conventional debris or core catching tool, and including: a tubular body having its upper end threadedly connected to the lower end of the pipe string, and having its lower end connected to the upper end of said tool; an axial bore in the upper portion of said body; a reduced upwardly presented shoulder in said bore and forming a ball seat; a second bore extending axially through the body below said seat; radially spaced fluid outlet ports extending outwardly through the wall of the body from a point above said ball seat; a tubular sleeve slidably disposed in said upper bore and having a plurality of channels formed within the confines of its wall and extending from end to end thereof; a ball seat on the upper end of said sleeve inside of the annular ring of channel ends; a resilient packer around the body, said packer connected to the sleeve and expandable by downward movement thereof; and radially spaced vertical ports within the confines of the wall of said body, said ports extending upwardly from the lower bore to a point above said packer, and thence outwardly through the body wall above said packer.

7. Structure as specified in claim 6 and: a ball adapted to be dropped through the pipe string, through said sleeve, and through the upper bore, into seated position upon the lower seat, after which any fluid pumped downwardly through the string is forced outwardly through said ports to the annular space in the well casing, said fluid thence traveling upwardly through the lower end of said tool to the lower bore of the mechanism and into said passages, a second ball of larger diameter adapted to be dropped into seated position upon said sleeve, whereby downwardly traveling fluid in said string acts to move the sleeve downwardly to expand the packer into sealing engagement with the well casing, with the channels in the sleeve wall admitting downward circulation of the fluid from the string to the upper bore of the body, after said larger ball is seated and the packer is expanded.
